UNITED STATES PATENT OFFICE

GREENLEAF WHITTIER PICKARD, OF AMESBURY, MASSACHUSETTS, ASSIGNOR TO WIRELESS SPECIALTY APPARATUS COMPANY, OF BOSTON, MASSACHUSETTS, A CORPORATION OF NEW YORK.

RADIO TELEGRAPHY AND TELEPHONY RECEIVER.

1,184,376.

Specification of Letters Patent.

Patented May 23, 1916.

Application filed March 28, 1914. Serial No. 827,845.

To all whom it may concern:

Be it known that I, GREENLEAF WHITTIER PICKARD, a citizen of the United States of America, and a resident of the town of 5 Amesbury, Massachusetts, have invented certain new and useful Improvements in Radio Telegraphy and Telephony Receivers, the principles of which are set forth in the following specification and accompanying 10 drawings, which disclose the form of the invention which I now consider to be the best of the various forms in which the principles of the invention may be embodied.

This invention relates to improvements in 15 receiving apparatus for radio telegraphy and telephony, and consists of the apparatus and arrangements thereof disclosed herein, the object of the invention being to provide simplified and more efficient apparatus.

Of the drawings, Figures 1, 2 and 3 are diagrammatic illustrations of the invention, Figs. 1 and 2 being modifications.

In Fig. 1 an inductance coil or receiving 25 coil 1 is connected between ground G and aerial or antenna A.

A second or potential-raising coil 2 has connected to one of its ends the receiving 30 apparatus comprising detector D, telephone T and potentiometer consisting of resistance R and battery B. The other end of this coil 2 is free, *i. e.*, not connected to any circuit.

A third coil 3 may have one terminal connected to ground at C, as shown, the other terminal being left free. I have found that better results are accomplished by thus dispensing with the closed or secondary circuit heretofore employed.

Each of coils 1 and 3 is adjustable with 40 respect to and inside of fixed coil 2, as indicated by the two double arrows.

The coil or winding 1 is preferably 45 smaller in diameter than coil 2, and may slide inside the latter to vary the coupling between these coils 1 and 2. If coil 2 is (as it may be) four and one-half inches in diameter, coil 1 is preferably about three inches in diameter. This provides a very 50 loose coupling between coils 1 and 2, with substantially no change of the period of coil 2, and gives extremely high selectivity.

Coil 1 is of any suitable winding, its construction, and adjustment to transmitter

waves of different lengths as indicated by 55 the arrow, being that of any ordinary antenna coil as used heretofore.

Coil 2 is a long winding of fine wire, and has a high inductance (19,500 microhenries is suitable).

The third coil 3 is preferably constructed 60 of a few turns of large or flat wire, so that its natural period will be high, corresponding to an extremely short wave length. In proportion as this coil might consist of 65 fine wire of many turns, it would absorb energy by coming in tune with the antenna circuit at some particular length of transmitted waves. This coil 3 is preferably only 70 sufficiently smaller in diameter than coil 2 to permit it to slide inside coil 2, but so that the two coils may be brought very close together.

In use, the operator adjusts the relations 75 of coils 1, 2 and 3, and the detector D and potentiometer R, B until he obtains the best results, as indicated by telephone T, from any given transmission. No adjustment of the inductances of coils 2 and 3 is needed. If desired, the relation between coils 2 and 80 3 may be varied widely without any variation of the relations between coils 2 and 1, but the latter may be varied also if desired, or 1 may be varied without varying the relation between coils 2 and 3.

The detector D is preferably of a type 85 having high resistance and best operated by current of high potential, and connected as it is to one end of coil 2, is subjected to the large potential changes thereat. The detector may be any of the so-called crystal rectifiers, particularly those of higher resistance, such as my silicon detector; or it may be of the well known gas-rectifier type.

The proper end of the coil 2 for the connection of the detector depends on various 90 conditions, including the direction of winding of coil 2 relative to coil 1, the form of coil 2, its degree of proximity to coil 1 or other conductors, etc. As there are only two 100 ends of coil 2, the simplest way of determining the proper end to connect the detector is to try it on each end, the one giving the loudest signals in telephone T being of course, the more efficient.

In Fig. 2, the antenna circuit A, 4, G is like the antenna circuit A, 1, G of Fig. 1. Open circuited coils 5 and 6 are disposed on

opposite sides or ends of antenna coil 4. But coils 5 and 6 are connected together, and are wound in such directions that their outside ends are of opposite potentials, as indicated by the plus and minus signs. Coils 5 and 6 are connected together through detector D, around which telephone T is connected. The coupling between each of coils 5 and 6 with coil 4, may be varied, as indicated by the double arrows; and both couplings may be varied simultaneously.

In Fig. 3, the parts 9, 10, D and T, and the variable couplings indicated by the double arrows, are the same as in Fig. 2, but coils 9 and 10 have a direction of winding which makes their outside ends of the same instead of opposite potentials, as indicated by the plus signs by way of example. The antenna-ground circuit A—G has two branches, each containing an adjustable condenser K or K¹ and a coil 7 or 8. The variable coupling of coil 9 is with coil 7, and that of coil 10 is with coil 8. This modification is an embodiment of the form of Fig. 2, modified to adapt it for combination with an interference preventer which is of the ordinary form so far as concerns the antenna branch circuits. Thus, by detuning one antenna branch, say, A, K, 7, G signals

from distant stations will not have effect on coil 9, but full effect on coil 8. Any aperiodic impulse will divide substantially equally in the two branches of the antenna circuit, and will therefore cancel out so far as detector D is concerned, on account of the opposition of coils 9 and 10.

I claim:

1. In a radio receiving system, the combination with a receiving coil, of a separate and second coil coöperatively associated therewith and having one end free and a detector-indicator circuit unilaterally connected to one of its ends, and a separate and third coil coöperatively associated with the second coil and having one end free and the other end connected to earth, substantially as and for the purpose described, substantially as and for the purpose desired.

2. In a radio receiving system, the combination with a receiving coil, of two open-circuited coils arranged coöperatively to each other and to the receiving coil, a detector connected to an open-circuited coil and a coöperating indicator.

GREENLEAF WHITTIER PICKARD.
